Primary Examiner — Cynthia M. Chin(74) *Attorney, Agent, or Firm* — Kolitch Romano Dascenzo Gates LLC(57) **CLAIM**

The ornamental design for a fender for electric vehicle, as shown and described.

DESCRIPTION

FIG. 1 is a top, rear, and right side perspective view of the new design for a fender for electric vehicle;

FIG. 2 is a top, front, and left side perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is a top, rear, left side perspective view thereof; and, FIG. 10 is an enlarged view of the area indicated in FIG. 9. The dash-dash broken lines illustrate portions of the article that form no part of the claimed design.

The dot-dash broken lines illustrate the bounds of the enlarged view and form no part of the claimed design.

The shading lines shown in the drawings represent the approximate three-dimensional contour of the design, and are not intended to indicate surface decoration.
